[57] CLAIM

The ornamental design for a belt hanger, as shown and described.

DESCRIPTION

FIG. 1 is a perspective view of a belt hanger showing our new design; the broken line showing of belt is for illustrative purpose only and forms no part of the claim;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.
